UNITED STATES PATENT OFFICE

ROBERT R. DUNLOP, OF COLUMBUS, OHIO, ASSIGNOR TO THE JEFFREY MANUFACTURING COMPANY, OF COLUMBUS, OHIO, A CORPORATION OF OHIO

RESISTANCE UNIT

Application filed March 8, 1924. Serial No. 697,796.

The present invention relates to certain new and useful improvements in resistance units, of the class which is especially adapted to use with electric motors, and similar apparatus, subject to the severe conditions obtaining in the narrowly limited space available in coal mines and the like.

The especial object of this invention is to provide a wire resistance unit of large capacity and small dimensions, having great heat resisting capacity and mechanical strength combined with convenience and flexibility of design.

The means whereby I attain this object are fully set forth in the following specification and illustrated in the accompanying drawings of which—

Fig. 1 is a side view of a resistance element embodying my invention.

Fig. 2 is a view of the lateral edge of the device illustrated in Fig. 1, looking in the direction of the arrow of Figure 1.

Fig. 3 is an end view of the device illustrated in Fig. 1.

Fig. 4 is a sectional view taken along the line IV—IV of Fig. 1.

Fig. 5 is a detail of the porcelain insulator forming a part of my improved resistance unit.

Fig. 6 is a fragmentary sectional view of a modified form of resistance unit coming within the spirit of my invention.

Like numerals refer to similar parts in the several figures.

In the drawings the numeral 1 refers to a frame, of generally rectangular outline, which is preferably made of cast iron but which may be formed of any other material suitable to the conditions of operation.

Upon the frame 1 are mounted a plurality of porcelain insulating blocks 2 each having a longitudinal groove 3 adapted to engage the edges of the frame 1. The insulators 2 are preferably made in relatively short sections

for convenience of manufacture, but if preferred they may be made in a single piece extending the length of the frame 1. The resistance wire 4 is wound upon the insulators 2 which are provided with spaced apart

transverse grooves 5 adapted to receive the

folds of said wire and hold them in spaced relation to each other. Clamping members 6 and 7, drawn together by suitable means such as the machine screw 8, engage the insulator blocks 2 to hold them in position upon the frame 1. The clamping members 6 and 7 at the left hand end of Figure 1 are viewed from the back where the clamping screws 8 thereof do not show, the purpose of this arrangement being to bring the binding posts 9 of these two clamping members in position to receive the wire 4 more directly. Binding posts 9 formed on the clamping members 6 afford fastenings for the ends of the wire 4 whereby said wire is connected both electrically and mechanically to said clamping members. Other binding posts 10 formed on the clamping members 6 serve to connect the resistance wire 4 with the conductors of an external circuit.

The resistance wire 4 is preferably composed of an alloy having high specific resistance and low affinity for oxygen thereby adapting the resistance unit to use at temperatures producing a low degree of incandescence without material deterioration. At such temperatures the buckling of the wire 4 due to its expansion, may possibly cause contact between adjacent folds of said wire, caus-

ing short circuits and producing arcs which render the apparatus unfit for use in the explosive gaseous and dust laden atmosphere commonly encountered in coal mines, and tending to burn the wire and thereby destroy the resistance unit. To prevent the forming

of such short circuits I have provided relatively short insulating collars, or beads 11 which are strung upon the wires 4 between the insulators 2. These beads are formed of heat resisting insulating material, preferably of porcelain, and have an external diameter substantially equal to the space between alternate wires. These beads are spaced apart upon the wire 4 in such manner that the ends of the bead upon one fold of the wire engage the ends of the beads upon the adjacent folds thereby holding the beads in spaced relation to each other and exposing the greater portion of the surface of the wire to the cooling effects of the atmosphere. The sleeves 11 on

the end strands of resistance wire are arranged in contact with each other, instead of being spaced as on the other strands, so as to retain the sleeves of adjacent strands in spaced relation to each other.

- 5 Formed on the frame 1, preferably at the corners of the frame, are laterally projecting bosses 12 having apertures through which the bolts 13 may project to attach the resistance unit to any preferred support such as the machine frame 14. Preferably there is interposed between the bolts 13 and the metal of the frame 1 suitable insulators such as the mica tube 15 and the mica washers 16 to further 10 guard against electrical connection between the resistance wire 4 and the machine frame 14. If desired, two or more units may be stacked together, as shown in Fig. 1, the bolts 13 being of sufficient length to extend through 15 the bosses 12 of all of the frames 1, and insulating washers 17 may be inserted between adjacent frames 1 to further guard against short circuits.

It is to be understood that I do not limit myself to the precise construction above described, since these devices may be subject to wide variation without departure from the spirit of my invention. One such modification is shown in Fig. 6 of the drawing where- 20 in divergent flanges 18 are formed along the lateral edges of the frame 1^a, and the insulator blocks 2^a are shaped to fit the V-shaped groove formed thereby.

By the above described construction I have 25 provided a simple, durable and convenient resistance unit, of small dimensions and great capacity, adapted to withstand the severe strains and shocks encountered in mining machine practice, and suitable for use in the 30 gaseous and dust laden atmosphere commonly found in coal mines and the like.

What I claim is:—

1. In a resistance unit, the combination of a frame, insulating blocks arranged along 40 outer substantially parallel edges of said frame, a resistance wire wound about said frame in contact with said blocks and tending to retain the latter against the edges of the frame, and interconnecting tension means 45 other than the resistance wire between opposite blocks for positively holding the latter against the frame edges.

2. In a resistance unit, the combination with a flat frame having two substantially 55 parallel edges, insulating blocks positioned upon said parallel edges, a resistance wire wound around said frame and engaging said blocks, and fastening means adapted to hold said insulating blocks in position upon said 60 frame, said fastening means being also adapted to prevent the unwinding of said wire and to operatively connect it with the conductors of an external circuit.

3. In a resistance unit, the combination 65 with a flat frame having two substantially

parallel edges, insulating blocks positioned upon said parallel edges, clamping members adapted to engage said insulating blocks and hold them in place upon said frame, a resistance wire wound around said frame and engaging said blocks, means to attach said wire to said clamping members, and separate means to connect said clamping member with the conductors of an external circuit.

4. In a resistance unit, the combination of a frame, insulating blocks arranged along outer substantially parallel edges of said frame, a resistance wire wound about said frame in contact with said blocks and tending to retain the latter against the edges of the frame, and clamp means between opposite blocks for positively holding the latter against the frame edges, said clamp means comprising a pair of substantially parallel arms and adjustable means for securing the intermediate portions of the arms together, the ends of the arms being engaged over the outer faces of said blocks.

In testimony whereof I have hereunto set my hand.

ROBERT R. DUNLOP.
